UNITED STATES PATENT OFFICE.

GARRET SCHENCK, OF MILLINOCKET, MAINE.

BARKING-MILL.

1,120,631.

Specification of Letters Patent. Patented Dec. 8, 1914.

Application filed November 24, 1913. Serial No. 802,586.

To all whom it may concern:

Be it known that I, GARRET SCHENCK, a citizen of the United States, residing at Millinocket, in the county of Penobscot and 5 State of Maine, have invented an Improvement in Barking-Mills, of which the following is a specification.

This invention relates to barking mills for removing the bark from blocks of wood 10 which are used in the production of pulp for the manufacture of paper.

The invention has for its object the production of a mill adapted for continuous operation, the wood blocks being fed in at one 15 end and discharged from the other end; also, the production of a mill involving a new principle of operation, in that the bark is removed from the blocks by a tumbling action in the open air and the bark which 20 is removed from the blocks is discharged from the mill by gravity, the barking-operation being a dry one instead of a wet one such as heretofore practised.

In one embodiment of my invention, 25 which is here shown for the sake of illustration, a long tumbling-chamber is employed, which is open at its ends, to admit of the blocks being fed in at one end and discharged from the other end, and is arranged in a slightly inclined position and 30 is adapted to be rotated slowly to cause the blocks to tumble over and upon each other and against the wall of the chamber, and to move them along from one to the other 35 end thereof while they are being tumbled, and has openings arranged at intervals throughout its length, through which the detached pieces of bark escape by gravity.

Figure 1 is a side elevation of a barking 40 mill embodying this invention. Fig. 2 is a right hand end-view of the mill. Fig. 3 is a sectional detail of said right hand end-portion of the mill. Fig. 4 is a left-hand end-view of the mill. Fig. 5 is a sectional detail of said left-hand end-portion of the mill.

In the embodiment of my invention shown in Fig. 1, the tumbling-chamber consists of four cylindrical pipe-sections 10, 12, 14 and 50 16, although any other number may be employed. Each section may be composed of several short cylindrical sections of pipe telescopically arranged and secured together; or they may be otherwise constructed. The several pipe-sections 10, 12, 14 and 55 16 are arranged in alinement to enable the

blocks to move from one to the next section throughout the entire length of the mill, and said sections are arranged in a slightly inclined position to facilitate such movement of the blocks, and they are separated from each other short distances to provide openings through which the pieces of bark fall by gravity. As the pieces of bark which are knocked off of the blocks vary 60 greatly in size, and it is necessary to provide for the escape of the largest pieces, these openings, which it will be observed, are co-extensive with the entire circumference of the sections, are amply sufficient; 65 and furthermore, as they are arranged transversely with respect to the sections, they provide for the quick and complete discharge of the pieces of bark, which have accumulated in the sections in rear of them, as 70 the sections rotate. However, it is obvious that the openings may be otherwise formed and arranged, and if it is not desired to discharge the detached bark throughout the length of the mill, the openings may be 75 omitted, although the efficiency of the mill is diminished. The pipe-sections, which serve as the tumbling or debarking sections are preferably imperforate, and their interior walls are made smooth or devoid of 80 projections or indentations, which admits of the blocks and the detached bark being easily moved along in a direction toward the exits thereof, where the detached bark is discharged, and such construction is of ad- 85 vantage for the reason, that the blocks are prevented from clogging, and pieces or fibers of the wood are not chipped off during the tumbling action. Furthermore such construction of mill provides for success- 90 95 sively discharging the detached bark at intervals, and such successive operations enables the employment of large discharge openings for the detached bark, and is contrasted with a mill wherein the debarking 100 and discharging operations are both substantially continuous.

In the mill, as represented in Fig. 1, the right hand end thereof is the inlet, and at said end an annular plate 18 is secured having a center-hole 20, through which the wood blocks are fed in. Said plate partially closes the end of the pipe-section to which it is attached, and serves as a retaining-plate for the blocks. The left hand end of the mill is the exit and at said end an annular plate 22 is provided having a

center-hole 24 through which the wood blocks are discharged. Said plate partially closes the end of the pipe-section to which it is attached, and serves as a retaining-plate for the blocks. Said plate 22 is not attached directly to the end of the pipe-section as is the plate 18, but is supported in fixed position in front of said pipe-section by brackets 26, thereby providing an opening between the end of the pipe-section and the plate for the escape of the pieces of bark, said opening being substantially the same as the openings before described, which are arranged at intervals along the chamber. Each pipe-section has arranged on its circumference flanged rings 30, there being two such rings shown on each pipe-section which are arranged in parallel relation, and disposed near the ends of the sections, and said rings rest upon flanged rollers 32 secured to shafts 33, which are positively rotated. The weight of the pipe-sections, particularly when loaded with the wood blocks, is sufficient to enable them to be rotated by frictional engagement with the rotating rolls, although in lieu of friction gearing such as described any other form of gearing may be employed for rotating the pipe-sections. As here shown, it will be noted that the pipe-sections are made independent of each other and are, therefore, independently rotatable but ordinarily they will be rotated in unison, as they are rotated by means common to all of them, but independent rotation of the sections, instead of being a disadvantage, is an advantage as the blocks which extend across the openings are so interlocked with other blocks in the sections that independent movement of one section relative to the other will accelerate the tumbling of the blocks.

The operation of the mill is as follows:— While the tumbling-chamber is rotating the wood blocks are fed in through the center-hole in the retaining-plate at the upper end and are caused to tumble over and upon each other, and against the wall of the chamber and to move along to the lower end thereof, where they are discharged through the center-hole in the retaining-plate thereat, and while being tumbled and moved along the bark is removed from them, and the pieces of bark fall by gravity through the openings.

It will be observed that the several pipe-sections composing the tumbling-chamber are loosely and independently supported upon the friction driving rolls and may be separately removed therefrom for any desired purpose; and that the open spaces between the sections are continuous, so that the pieces of bark are free to fall all the time the chamber is rotating.

I claim:—

1. A barking mill consisting of a long

tumbling-chamber, open at its ends to receive the blocks at one end and permit of their discharge from the other end, said chamber being arranged in a slightly inclined position, and means to rotate said chamber slowly to cause the blocks to tumble over and upon each other and against the wall of the chamber and to move them from one to the other end of the chamber, said chamber being devoid of block-clogging and chipping-portions, substantially as described.

2. A barking-mill consisting of a long tumbling-chamber, comprising a plurality of tumbling-portions, said chamber being open at its ends to receive the blocks at one end and permit of their discharge from the other end, and arranged in a slightly inclined position, and said chamber having openings at intervals, widely spaced apart, and means to rotate said chamber slowly to cause the blocks to tumble over and upon each other and against the walls of the tumbling-portions, and to move them from one to the other end of the chamber, across the openings, whereby the bark-discharging operations are successively and repeatedly performed, substantially as described.

3. A barking mill consisting of a long tumbling-chamber, open at its ends to receive the blocks at one end and permit of their discharge from the other end, and having retaining plates partially closing said open ends and having an opening immediately in rear of the retaining-plate at the exit, which is substantially co-extensive with the circumference of the chamber, said chamber being arranged in a slightly inclined position, and means to rotate said chamber slowly to cause the blocks to tumble over and upon each other and against the wall of the chamber and to move them from one to the other end of the chamber, substantially as described.

4. A barking-mill consisting of a long tumbling-chamber, open at its ends to receive the blocks at one end and permit of their discharge from the other end and having its interior wall devoid of block-clogging and chipping portions, said chamber being arranged in a slightly inclined position, and having openings arranged at intervals, widely spaced apart, and means to rotate said chamber slowly to cause the blocks to tumble over and upon each other and against the wall of the chamber and to move them from one to the other end of the chamber, across the openings, and cause the detached bark accumulating in the tumbling-portions of the chamber to escape at the openings, substantially as described.

5. A barking mill consisting of a long cylindrical open-ended tumbling-chamber, rotatable about an axis slightly inclined to the horizontal, and having long narrow

openings arranged at intervals, and means to rotate said chamber to tumble the blocks over and upon each other and against the wall of the chamber, and to move them along from one to the other end of the chamber, and cause the piece of detached bark to fall by gravity through the openings, substantially as described.

6. A barking mill consisting of a long open-ended tumbling chamber rotatable about an axis slightly inclined to the horizontal, and having narrow elongated openings arranged at intervals, and means to rotate said chamber to tumble the blocks over and upon each other and against the wall of the chamber, and to move them along from one to the other end of the chamber, and cause the pieces of detached bark to fall by gravity through the openings, substantially as described.

7. A barking mill consisting of a long open-ended tumbling chamber rotatable about an axis slightly inclined in the horizontal, and having narrow elongated openings arranged at intervals transversely with respect to the chamber, and means to rotate said chamber to tumble the blocks over and upon each other, and against the wall of the chamber, and to move them along from one to the other end of the chamber, and cause the pieces of detached bark to fall by gravity through the openings, substantially as described.

8. A barking mill consisting of a long open-ended tumbling chamber rotatable about an axis slightly inclined to the horizontal, and having narrow openings arranged at intervals co-extensive with the circumference of the chamber, and means to rotate said chamber to tumble the blocks over and upon each other, and against the wall of the chamber, and to move them along from one to the other end of the chamber, and cause the pieces of detached bark to fall by gravity through the openings, substantially as described.

9. In a barking mill the combination of a plurality of cylindrical open-ended tumbling-sections arranged in alinement and in a slightly inclined position, said sections having open spaces arranged at intervals, and means to rotate said sections, substantially as described.

10. In a barking mill the combination of a plurality of open-ended pipe-sections arranged in alinement and in a slightly inclined position, separated from each other short distances to provide open spaces between them, and means to rotate the sections, substantially as described.

11. In a barking-mill, the combination of a plurality of imperforate open-ended tum-

bling-sections arranged in alinement, and in a slightly inclined position, having openings between them, and means to rotate said sections, substantially as described.

12. In a barking mill, the combination of a plurality of independent open-ended pipe-sections arranged in alinement and in a slightly inclined position and separated from each other to provide open spaces between them, and means to rotate each section arranged to permit independent rotary movement of the sections, substantially as described.

13. In a barking-mill, the combination of a plurality of open-ended tumbling sections arranged in alinement with openings between them, driving-means co-extensive with all said sections with which the sections are connected by frictional engaging means, substantially as described.

14. In a barking mill, the combination of a plurality of pipe-sections arranged in alinement and in a slightly inclined position, annular plates with center-holes arranged at the outer ends of the end-sections to partially close them, the annular plate at the discharge end being supported a short distance from the section to which it is attached to provide an open space between it and the section, and means to rotate all of the sections, substantially as described.

15. A barking mill consisting of a long tumbling chamber open at its ends to receive the blocks at one end, and permit of their discharge from the other end, and arranged in a slightly inclined position, and having a narrow opening adjacent its exit, which is substantially co-extensive with the circumference of the chamber, through which the detached pieces of bark fall by gravity, and means to rotate said chamber, substantially as described.

16. The process herein described of debarking logs which consists in removing the bark from the logs while in a dry state by a tumbling action and segregating the detached dry bark from the logs by gravity during the debarking operation.

17. The process herein described of debarking logs which consists in subjecting the logs while in a dry state to a tumbling action thereby to remove the bark from the logs and segregating the detached bark by gravity at intervals during the tumbling action.

In testimony whereof, I have signed my name to this specification, in the presence of two subscribing witnesses.
